UNITED STATES PATENT OFFICE.

RUSSELL H. CLEMINSHAW, OF SHAKER HEIGHTS, OHIO, ASSIGNOR TO THE CLEVELAND ELECTRIC MOTOR COMPANY, OF CLEVELAND, OHIO, A CORPORATION OF OHIO.

SAND-MIXING MACHINE.

Application filed March 17, 1927. Serial No. 176,011.

This invention as indicated relates to a sand mixing machine. More particularly it comprises an apparatus adapted to engage into and mix foundry sand and which also is adapted to pile the same in a restricted space when the floor space is required for other purposes.

Sand mixing machines, sometimes designated sand cutting machines, of construction similar to that herein described, have heretofore been used; but in most instances the mixing cylinder drive of such machines has been by means of worm gears or through a beveled drive, wherein a speed reduction from the motor was provided for. In such constructions, however, the drive is irreversible and frequent breakage of the gear teeth and driving mechanism has resulted because of the great stresses which occasionally are placed upon the cutter when hardened areas or foreign matter are encountered in the sand pile.

The present invention has for its principal object a construction which will readily absorb unusual shocks or stresses imposed upon the mixing member by transmitting the strains along the driving means to the motor and permitting the stoppage or reversal of the mixing means without causing any harm to the mechanism. This function is accomplished by connecting the driving motor directly with the sand mixing member through sprocket wheels of suitable diameter to provide for necessary gear reduction, thus permitting unusual stresses applied to the mixing member to be transmitted directly to the armature shaft of the motor, which, as will be understood, may turn freely and may be stopped or reversed without damage to the mechanism.

Another object of the invention is to provide a central drive for the mixing cylinder which may be enclosed to prevent the entrance of grit. Another object of the invention is to provide a central member of plow-like shape which will serve to form a central furrow through the sand pile and which will thus prevent an excess of material to be piled at that point.

A further object of the invention is to provide an over-load switch in the circuit of the motor for driving the mixing cylinder

which switch will prevent injury to the motor when the mixing cylinder is suddenly stopped as by encountering foreign matter or an area of hard sand. Other and further objects of the invention will appear in the course of the following description.

To the accomplishment of the foregoing and related ends, said invention, then consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 of the drawing is a front elevation showing a sand mixing machine embodying the principles of my invention; Fig. 2 is a side elevation of the machine shown in Fig. 1; and Fig. 3 is a diagrammatic view of the motor circuit including an overload switch as used with said apparatus.

As is clearly shown in the drawing, the sand mixing apparatus comprises a frame 1 supported upon a pair of large driving wheels 2 at its forward end and having a pair of small sized wheels 3 at its rearward end, each independently mounted in a swivelling support 4 to permit the same to act in the manner of casters.

The frame carries at its rearward end a platform 5 upon which driving mechanism for the respective drive wheels is mounted. Each wheel is preferably provided with an individual motor as is more particularly described in a companion application. Each motor 6 through suitable gearing 7 drives a countershaft 8 upon the end of which a driving pinion 9 is mounted. The pinion, engages internal gear teeth 11 upon the driving wheel. Through suitable controlling means (not shown) the driving wheels may be simultaneously or individually operated thus permitting the machine to be turned or maneuvered as desired.

The forward end of the platform is provided with journals 12 within which the axle 13 of the driving wheels is received. Upon the central portion of said axle, a sleeve 14 is mounted, which sleeve has an upwardly

projecting arm 15 adapted to support the motor 16 for driving the mixing cylinder. The sleeve also carries arms 17 at its extreme ends extending downwardly and provided at the free ends with journals 18 within which the shaft 19 of the mixing cylinder 20 is mounted.

Centrally of the mixing cylinder shaft, a sprocket wheel 21 is provided, said sprocket wheel being of suitable size relative to a similar sprocket wheel 22 on the shaft of the driving motor to provide for a suitable gear reduction. A sprocket chain 23 connects the respective sprocket wheels and is enclosed in a dust-proof casing 24. The lower end of the casing is preferably provided with a sharpened edge 25 which may readily enter the sand heap without causing undue friction. The casing itself is made 20 of very narrow width in order to present no obstruction to the apparatus being moved through a sand pile. The casing is in effect a central plow and is adapted to be forced through the sand pile and form a central furrow. This action serves to prevent the accumulation of an excess quantity of sand at a central point.

It will be noted, particularly from Fig. 2, that the driving motor for the mixing cylinder is swung in a position slightly rearward of a driving shaft which thus permits the motor to serve as a counterbalance for the mixing cylinder.

As has been indicated, the apparatus is moved from point to point by means of the driving motors and an independent motor serves to drive the mixing cylinder. The power is obtained from the usual lighting terminals and is carried to the machine by means of a flexible cable (not shown). The details of the power mechanism for the driving wheels as heretofore stated is the subject matter of a separate application and forms no part of the present invention which as has been indicated relates to the means to relieve the apparatus from shock or injury when unusual conditions are encountered.

It will be obvious from the construction above described that when the mixing member meets with resistance that the strain will be applied to the sprocket wheels and

sprocket chain and transmitted directly to the armature shaft of the driving motor. Inasmuch as no irreversible or slowly acting gearing is interposed the armature will be retarded, stopped or reversed, but no breakage will occur. The motor construction is such that the stopping of the armature or the reversal of the same brings about no undue harmful effects and thus all shocks are taken up and all danger of breakage of the driving mechanism is obviated.

Through the use of an overload switch 31, as is shown in Fig. 5, the circuit connections of the motor will be broken when an excess of current is present in the line. The switch as shown is positioned in the line 32 and is actuated by a coil 33 in the line 34, when through sudden stoppage or reversal of the motor, an excess of current is caused to flow through said coil, or where for any reason there is an increase in the line current.

The switch has been illustrated as used in a three-phase alternating current line but it is obvious that it could also be used in other circuits with like effect.

Other modes of applying the principle of my invention may be employed instead of those explained, change being made as regards the mechanism herein disclosed, provided the means stated by any of the following claims or the equivalent of such stated means be employed.

I therefore particularly point out and distinctly claim as my invention:

1. An apparatus of the character described having in combination a wheeled support, a sand mixing cylinder mounted on said support, a central drive for said cylinder, an enclosing casing for said drive, said enclosing casing having its lower end sharpened to provide a sand distributing member.

2. An apparatus of the character described having in combination a wheeled support, a sand mixing cylinder mounted on said support, and non-rotatable means engaged centrally with said mixing cylinder and projecting downwardly to provide a sand distributing means centrally of said cylinder.

Signed by me this 12th day of March, 1927.

RUSSELL H. CLEMINSHAW.
